AGRICULTURAL MACHINE

Kenneth L. Magee, Burlington, Iowa, assignor to
 J. I. Case Company, Racine, Wis., a corpora-
 tion

Application October 20, 1941, Serial No. 415,732

3 Claims. (Cl. 56—18)

1

The present invention relates to agricultural machinery and more particularly to corn pickers, and an object of the invention is to generally improve the construction and operation of mechanisms of this class.

A further object of the invention is to improve the construction of corn pickers, particularly as regards the frame elements and adjusting expedients.

Further objects are to provide a new and improved tubular type frame for a corn picker; expedients for adjustably supporting the tubular frame; expedients for supporting a power take-off mechanism from such a frame; expedients for connecting a draw bar to such a frame; an arrangement of an elevator in combination with the frame and drawbar, such that the elevator will maintain certain relations with the other parts when the latter are adjusted; and expedients for realizing the above objects.

Further objects and advantages will be apparent from the following specification and annexed drawings in which:

Figure 1 is a left side elevation of a machine with parts removed, illustrative of the invention.

Fig. 2 is a plan view of the frame and draw bar, the parts characteristic of the corn picker being removed or broken away to avoid interference with the showing of the frame and draw bar parts.

Fig. 3 is an enlarged vertical sectional view taken from the left in Fig. 2 just inside of the left wheel.

Fig. 4 is a longitudinal axial section of a link member indicated in Fig. 1.

Fig. 5 is a view similar to Fig. 2 showing a modified construction of wagon hitch.

Fig. 6 is a view similar to Fig. 1 but with parts omitted, also showing the modified construction of wagon hitch.

Similar reference characters have been applied to the same parts throughout the specification and various figures of the drawings.

As seen in Fig. 1, the machine illustrative of the invention is a corn picker having a snapping portion generally designated as 10, an elevator generally designated as 11, a fan 12 for separating trash from the snapped ears and a hopper 13 for receiving ears from elevator 11 and conducting them to a discharge elevator generally designated as 14. The parts so far described with the exception of elevator 14 are substantially conventional and well-known and should not need to be further described.

The various units of the corn picker are assem-

2

bled on a frame element generally designated as 15, which is supported by wheels or other ground engaging elements as for example 16, and a draw bar generally designated as 17 is connected to frame 15 for propelling the machine and guiding and controlling it.

Frame 15 as more particularly shown in Fig. 2 comprises a pipe or tube element 18 which in the present instance extends transversely of the direction of progress of the corn picker and has attached thereto, as will appear, stub axles 19 and 20 on which are suitably journaled wheels 16—18. Tube 18 is thereby supported for movement over the ground and as will be apparent serves as the main foundation element for the other units of the corn picker.

Different conditions require different heights of the machine above the ground and for this reason axles 19 and 20 are adjustably connected to tube 18, the structure associated with the two axles being identical, only one will be described. Axle 20 is welded or otherwise suitably fixed in the present instance with a channel element 21 which extends transverse to the axle and substantially vertically. Channel 21 is engaged with a channel or other element 22 welded or otherwise suitably fixed to tube 18. As more particularly shown in Fig. 3, channel members 21 and 22 are fixed together by suitable means as bolts 23—23, channel member 21 being provided with a plurality of holes 24—24 whereby it may be bolted to member 22 in various positions to give a height adjustment of tube 18 relatively to the ground.

As above stated the picking units and other parts or units of the machine are secured to tubular element 18, and for this purpose plates or the like 25 and 26 are suitably fixed with tube 18 as by welding, and to which in the present instance the snapping unit 10 and elevator unit 11 and their connected parts are secured in any suitable manner not shown. Plates 27 and 28 are also fixed as by welding to tubular element 18 and support a gear box or transmission unit 29 constituting a part of a power take-off drive generally designated as 30. Thus it will be apparent that a plurality of machine units has been provided which are mounted in fixed positions on frame 15.

Draw bar 17, as particularly shown in Fig. 2, is connected with tube element 18 at spaced points by means providing for universal movement between the draw bar and the tube. For example, ears 31 and 32 suitably united to tube 18, as 55 by welding, support a bolt or the like 33 on which

is journaled a fitting 34 for rocking movement in a vertical plane. Fitting 34 has journaled therein a pin 35 fixed with draw bar 17. By virtue of this construction, tube 18 and the attached corn picker parts may be rocked in a vertical plane for adjusting purposes without interference from draw bar 17. In like manner, ears 36 and 37 are fixed with tube 18 spaced from above mentioned ears 31 and 32 and support a bolt 38 on which is journaled a fitting 39. Fitting 39 has journaled therein a pin 40 which is fixed with a channel or similar member 41 fastened to draw bar 17 by bolts or the like 42—42. Draw bar 17 is generally triangular in shape, having a side 43 engaged with above mentioned pin 35 and a side 44 to which is bolted above mentioned channel member 41. A plurality of holes 45—45 is provided for bolts 42. With bolts 42 removed, draw bar 17 can be swung laterally about pin 35 to change the degree of offset of the machine from a tractor or other drawing element connected with draw bar 17 at 46. Bolts 42 being replaced in the desired holes, a laterally rigid connection is afforded between draw bar 17 and tubular element 18.

A lever 47, Fig. 1 is provided for adjusting the position of the machine parts including tube 18, the lever being pivoted at 48 to draw bar 17 and cooperating with a quadrant 49, suitable or well-known detent or latch mechanism indicated at 50 being provided for locking lever 47 at desired positions on quadrant 49. A link generally designated as 51 pivoted at 52 to lever 47 is also pivoted at 53 to an arm 54 of a bell crank pivoted at 55 to draw bar 17. An arm 56 of the bell crank is connected by a link 57 to an arm 58 rigidly connected in any suitable manner with above mentioned snapping unit 10. Since snapping unit 10, as above described, is rigidly fixed with tube 18, through the medium of plates 25 and 26, adjustment of lever 47 through bell crank 54 and the attached linkage, will cause rocking movement of tube 18 as well as the desired vertical adjustment of snapping unit 10.

To assist in supporting the weight of snapping unit 10, a spring 59 is tensioned between arm 54 and an anchorage 60 in the present instance on draw bar 17. The tension of spring 59 will tend to raise snapping unit 10. In the present instance this tension is made sufficient to overcome the weight of snapping unit 10 and to raise it from the ground. Link 51 is made resiliently extensible so that snapping unit 10, although forced downwardly by link 51 against the tension of spring 59, may rise if it encounters an obstruction by effecting a lengthening of link 51.

As seen in Fig. 4, link 51 in the present instance is made in the form of a tube 61, having an ear portion 62 for pivotal attachment to lever 47 as above described, a pull rod 63 extending into the tube and having a washer or abutment 64 fixed therewith within tube 61. Tube 61 has a cap 65 at the end opposite ear 62 and through which rod 63 is slideable, and a spring 66 is compressed between abutment 64 and cap 65 so as to tend to force rod 63 into tube 61 at all times. Rod 63 can thus be pulled out of tube 61 to a substantial extent against the resistance of spring 66 by a force sufficient to overcome the compression of the spring.

Discharge elevator 14, as particularly shown in Fig. 2, is pivotally supported from tubular element 18. A framework generally designated as 67 is extended rearwardly and in the present instance fixed with above mentioned plates 27 and 75

28 and, conveniently, beneath tube 18. Frame 67 includes rearwardly extending side elements 68 and 69, and a rear cross element 70, a pivot shaft 71 being journaled in bearings 72 and 73 supported respectively on members 68 and 69. Shaft 71 forms a pivotal support for above mentioned discharge elevator 14 and may conveniently also form the power input or drive shaft for said elevator, a sprocket 74 being fixed with shaft 71 and driving a chain 75, Fig. 1, carrying buckets 76 or the like in well-known manner. Elevator 14 being otherwise well-known, no further description is considered to be necessary. Elevator 14 extends upwardly and rearwardly from its pivotal support on shaft 71 and may discharge into a wagon 77 drawn behind the corn picker. Adjustment to accommodate the height of wagon 77 may be effected by swinging elevator 14 about shaft 71, suitable means being provided as will appear.

For supporting elevator 14, a truss rod or the like 78 is pivoted to elevator 14 near the upper end thereof as at 79 and extends forwardly to a pivotal connection on the draw bar, in the present instance a pin or the like 80 being connected to quadrant 49 and on which truss rod 78 is pivoted. A stable arrangement is thus provided by means of which elevator 14 may extend over wagon 77 in an overhanging relation. Truss rod 78 in the present instance has a flattened portion 78^a provided with a series of holes 78^b for reception of pivot 79 for effecting adjustment of the position of elevator 14.

By virtue of the fact that truss rod 78 is connected to draw bar 17, which remains substantially stationary in a vertical direction because of its connection to the tractor, rocking movement of tubular frame 18 and the attached corn picker parts causes substantially no perceptible movement of the upper end 81 of elevator 14. This is so because pivot 71 is only a short distance from the center line of rocking movement of tube 18, namely axle 20, while pivot 79 at the outer end of elevator 14 is allowed no relative fore-and-aft movement because of its connection to draw bar 17. Consequently, the slight up and down movement of pivot 71 caused by rocking of tube 18 causes only a slight pivotal movement of elevator 14 about pivot 79. As will be apparent, the resulting movement of discharge end 81 of elevator 14 is negligible.

Above mentioned transverse element 70 of frame 67, Fig. 2, in the present instance is provided with an opening 82 which is engaged by a hook 83 or suitable fitting for connecting a wagon tongue 84. Opening 82 being substantially in direct line with portion 46 of draw bar 17, a direct straight line pull is obtained between the tractor and the attached wagon.

Elevator 14 may be braced against the very considerable swaying action induced by travel over rough ground by means of a strut 85, Fig. 5, fixed to elevator 14 at 86 and pivoted at 87 to a strut 88, in the present instance fixed to and extending rearwardly from above mentioned plate 25. As indicated, pivot 87 is located substantially in alignment with above mentioned shaft 71 so that free pivotal movement of frame 18 is provided without binding or distortion of the parts.

As seen in Fig. 5, a modified form of wagon hitch comprises a frame, generally designated as 89 attached to a draw bar 17^a in any well known manner as for example by welding, generally similar to above described draw bar 17, a side

member 90 engaging a side member 44^a of draw bar 17^a, and preferably also a rear cross brace 91 of the draw bar 17^a. Member 90 extends downwardly and rearwardly beneath tubular element 18 and connects with a rear cross member 92. Cross member 92 connects also with a side member 93 which extends forwardly beneath tubular element 18 as indicated in Fig. 6, and connects with a side member 43^a of draw bar 17^a. Cross member 92 has an opening 94 in which may be engaged a hook or other suitable fitting such as above mentioned hook 83. By means of this construction, the drag of the wagon is transmitted directly to draw bar 17^a and does not pass through any of the corn picker structure. Furthermore, the rocking of tubular element 18 for adjusting purposes does not change the height of the wagon hitch above the ground. Also, the pull of the wagon does not influence the adjustment of the machine by interfering with the rocking of tubular frame 18.

It is to be understood that various well-known mechanical expedients are contemplated as part of the illustrative machine and that connections from power take-off gear box 29 of well-known type will be provided to the various operative units of the corn picker. Since the latter form no part of the present invention, it is considered unnecessary to illustrate them.

The operation of the invention is thought to be clear from the above description, and it is understood that the same is illustrative merely and is not to be taken as limiting the invention in any manner. What is claimed as new and desired to be secured by Letters Patent of the United States is:

1. In an agricultural machine, a rocking frame member, ground engaging units supporting the frame member, machine units connected with the frame member to be supported thereby and including an elevator pivotally connected with the frame member and a draw bar pivotally connected to the frame member for propelling the same, means for rocking the frame for adjusting the position thereof relatively to the draw bar, and a connection directly between a point on the draw bar and spaced from the pivotal connection of the elevator to the frame, the elevator, for

maintaining the elevator substantially in predetermined relation to the draw bar regardless of the rocking of said rocking frame.

2. In a corn picker, a frame comprising a unitary element disposed transversely of the direction of progress of the machine, ground engaging elements supporting the frame, a draw bar pivotally connected to the frame, a plurality of machine units, including a snapping unit, rigidly connected with and supported by said frame in working relation to each other, a bell crank pivotally supported on said draw bar having a substantially horizontal arm and an upwardly extending arm, a connection from said substantially horizontally extending arm to said snapping unit for controlling the latter upon rocking of said bell crank, an adjusting lever mounted on said draw bar and a resiliently yieldable link connecting said adjusting lever with the upwardly extending arm of said bell crank for rocking said bell crank upon adjusting of said adjusting lever.

3. In a corn picker having a plurality of machine units, required to be maintained in predetermined operative relation with each other and including a set of gathering points, a transmission unit and an elevator unit, a frame for said machine comprising a tubular element to which said units are attached, said tube constituting a combined frame and axle for said machine and said elevator unit extending rearwardly and being pivotally connected to said frame, ground engaging supporting elements for said tube providing a rolling support for the machine, a drawbar pivotally attached to said tube, means for rocking said tube so as to tilt the entire machine with the exception of the drawbar for raising and lowering said gathering points without disturbing the operating relations between said units, and a connection directly between a point on the draw bar spaced from the pivotal connection of the draw bar to the frame and a point on the elevator spaced from the pivotal connection of the elevator to the frame for maintaining the elevator substantially in predetermined relation to the drawbar regardless of the rocking of said rocking frame.

KENNETH L. MAGEE.
